FIRE EXTINGUISHER

Filed Jan. 4, 1957

Fig. 2. Drawing of a cylindrical device with internal components and a small circular component labeled 19.

The drawing shows a cylindrical device with internal components labeled 14, 15, 16, and 17. A small circular component labeled 19 is shown separately.

A line drawing of a person from the side, facing right. The person is in a dynamic pose with one arm raised high and bent, and the other arm bent at the elbow with the hand near the head. Their legs are in a wide, dynamic stance with knees slightly bent. Arrows on the person's body indicate circular motion: one on the raised arm, one on the bent leg, and one on the torso, suggesting a circular movement like a turn or a circular dance step.

Fig. 4. Technical drawing of a device assembly. The drawing shows a top view of a horizontal frame with various components labeled with letters and numbers. On the left, a vertical assembly includes a coil (20), a tube (21), and a flange (22). A central horizontal component (25) is connected to the frame. On the right, a vertical tube (19) is connected to a flange (18). A horizontal tube (14) connects the central component to the vertical tube. Various labels include A, B, C, D, E, F, G, H, I, X, Y, and Z, along with numbers 10, 11, 12, 13, 14, 15, 16, 17, 18, 19, 20, 21, 22, and 23.

FIRE EXTINGUISHER

Fredwill Bittner, Los Angeles, Calif.

Application January 4, 1957, Serial No. 632,566

2 Claims. (Cl. 169—36)

This invention relates to a fire extinguisher and is more particularly concerned with a combination dry chemical and concussion fire extinguisher.

In many situations, fires can be momentarily arrested or subdued by a concussion and/or by the application or covering of the fire with a dry powder-like chemical, as for instance, sodium bicarbonate.

Ordinarily, in fires of any consequence, it is not possible to get close enough to the fire to suitably dust or cast a dry chemical, such as sodium bicarbonate, or it in a manner to achieve any suitable or advantageous results.

An object of the present invention is to provide a fire extinguisher construction adapted to distribute and dust a large area with a dry powder fire extinguishing chemical.

Another object of the present invention is to provide a fire extinguisher construction of the general character referred to that can be cast into or above conflagration to advantageously cover and extinguish the fire.

A further object of my invention is to provide an expendable combination concussion and dry chemical fire extinguisher construction which is easy and economical of manufacture, which is neat, compact and easy to store and handle, and which is both effective and dependable in operation.

A feature of the present invention is to provide a fire extinguisher having a frangible container filled with a suitable dry powdered fire extinguishing chemical and an explosive charge or bomb within the container and adapted, when ignited, to explode the container and distribute the chemical.

Another feature of my invention is to provide a casting cord with a handle on the fire extinguisher construction and adapted to facilitate slinging or casting the extinguisher into a fire.

The various objects and features of my invention will be fully understood from the following detailed description of a typical preferred form and application of my invention, throughout which description reference is made to the accompanying drawings, in which:

Fig. 1 is a perspective view of the fire extinguisher that I provide and showing it in a closed, sealed condition.

Fig. 2 is a perspective view of the fire extinguisher that I provide and showing it in an open or extended condition ready for use.

Fig. 3 is a perspective view showing a man casting the fire extinguisher as provided by the present invention.

Fig. 4 is an enlarged detailed sectional view of my fire extinguisher construction and taken as indicated by line 4—4 on Fig. 1.

Fig. 5 is an end elevational view taken as indicated by line 5—5 on Fig. 4.

The fire extinguisher provided by the present invention and illustrated throughout the drawings, includes, generally, an elongate cylindrical body A, a pair of longitudinally spaced partitions B and C within the body and defining a central chamber X and longitudinally outwardly opening end chambers Y and Z, and end closures

2

D and E engageable in the ends of the body and normally closing the chambers Y and Z.

The fire extinguisher that I provide further includes, a charge F of dry, powder fire extinguishing chemical in the central chamber X, an explosive bomb G within the chamber X and imbedded within the dry chemical, a fuse H for the bomb G and extending through the partition C to occur within the chamber Z, and an elongate casting cord I fixed to and extending between the partition B and the closure D and adapted to normally occur within the chamber Y.

The body A is a simple, elongate tube of frangible material, such as paper, and is characterized by straight, cylindrical inner and outer walls 10 and 11 and flat, radially disposed ends 12 and 13.

The longitudinally spaced partitions B and C are like, oppositely disposed cup-shaped members, having flat, radially disposed bottoms 14 and longitudinally disposed annular flanges 15. The flanges 15 slidably engage the inner wall 10 of the body A.

The cup-shaped partitions B and C are engaged in the related ends of the body A so that they open outwardly and are engaged in the body so that the edges of the flanges 15 are spaced inwardly of the ends 12 and 13 of the body and establish annular shoulders 16 adapted to be engaged by and to stop the closures D and E, as will hereinafter be described.

In practice, the partitions B and C are secured in fixed position in the body as by the application of a suitable cement which establishes a seal between the partition and the body, and by a plurality of circumferentially spaced staples 17.

With the above relationship of parts, it will be apparent that the partitions B and C cooperate with the body A to define the central chamber X in which the fire extinguishing chemical F and the bomb G are contained and the longitudinally outwardly opening end chambers Y and Z in which the casting cord I and the fuse H are normally housed.

The fire extinguishing chemical F is a dry powdered chemical, such as sodium bicarbonate and is packed in the chamber X.

The bomb G is shown as a simple elongate cylindrical member of limited diameter and longitudinal extent and is arranged in the chamber X of the body A to occur along the central longitudinal axis of the body and in spaced relationship between the partitions B and C.

In practice, the bomb G can be in the nature of a large fire-cracker and is provided with an elongate fuse H which extends through a suitable port or aperture 18 in the partition 14 and so that the free end of the fuse occurs within the chamber Z.

In assembling or building the fire extinguisher that I provide, the partition B is secured in the body A, then a portion of the chemical F is inserted into the chamber Y and is packed in the end of the chamber adjacent the partition B, next the bomb G is positioned in the chamber; and then the remainder of the chemical F is inserted and packed in the chamber to occur around and to cover the bomb. After the chemical and the bomb are packed and positioned in the body in the manner set forth above, the fuse H of the bomb G is engaged through the aperture 18 in the partition C and the partition is engaged in the body, against the chemical F packed therein, and is fixed in position.

The closure E for the chamber Z and adapted to normally close the chamber and protect the fuse H housed therein, is a flat, disc-shaped paper or fiber board member and is adapted to be press fitted into the chamber Z from the outer end thereof, to establish bearing engagement against the shoulder 16 in the chamber established

by the flange 15 of the partition C. The closure E is provided with a pull tab 19 at one side thereof, which tab projects longitudinally outwardly from the end 13 of the body and is adapted to be engaged between the fingers to remove the closure and thereby expose the fuse H for the bomb G.

The closure D for the chamber Y and adapted to normally close the chamber and house the casting cord I is similar to the closure E for the chamber Z, that is, it is a flat, disc-shaped paper or fiber board member adapted to be press fitted into the chamber Y from the outer end thereof, to establish bearing engagement against the shoulder 16 in the chamber, established by the partition B. The closure D, like the closure E, is provided with a pull tab 20 at one side thereof to permit easy removable of the closure from the body when the extinguisher is readied for use.

The casting cord I fixed to and extending between the partition B and closure D is a simple cord or string of suitable size and strength. One end of the cord is engaged through an aperture 21 in the partition B and is knotted, as at 22, to prevent its withdrawal or separation from the partition, while the other end of the cord is engaged through a suitable aperture 23 in the closure D and is knotted, as at 24, to prevent its withdrawal or separation from the closure D.

With the above relationship of parts, it will be apparent that when the closure D is removed from engagement in the body A, the cord I is pulled out of engagement in the chamber Y and the closure D becomes a suitable handle at the free end of the cord. By engaging the closure D in the hand after it is removed from the body A, the operator or person putting the extinguisher to use can swing or cast the extinguisher into a fire, in the manner indicated by the arrows in Fig. 3 of the drawings.

In the preferred carrying out of the invention and to prevent the knot 22 from tearing the partition B or from being drawn through the aperture 21 in the partition, I provide an apertured back-up plate or washer 25 on the inner side of the partition and through which the cord I is engaged. In order that the knot 24 does not tear or pull out of engagement from the closure D, I provide an apertured back-up plate 26 on the outer side of the closure D and through which the cord I is engaged. In practice, it is preferred that the back-up plate 26 related to the closure D, be cemented to the closure so that it will not become displaced. It is also preferred that the plate 26 be elongate in form and so that the portions of the closure D occurring at the opposite side edges thereof can be easily and conveniently bent or folded over the side edges of the plate in the manner illustrated in Fig. 2 of the drawings, and so as to form a comfortable and easily gripped handle, by which the extinguisher can be hurled or cast.

In use, if it is desired to explode the extinguisher above the fire which is to put out, the fuse H is lit and after a predetermined length of time or count, the extinguisher is cast into the air above the fire. When the bomb G is ignited and the extinguisher explodes the concussion dampens the fire and permits the dry chemical to drop or settle in an efficient and effective manner.

In cases where it is not desired to explode the extinguisher in the air and where the fire is very dense, it is only necessary to throw or cast the extinguisher into the fire, whereupon the fuse will be lit and the extinguisher will explode in the desired manner.

From the foregoing, it will be apparent that I have invented a fire extinguisher which is both easy and economical of manufacture and which is both effective and dependable in operation.

Having described only a typical preferred form and application of my invention, I do not wish to be limited or restricted to the specific details herein set forth, but wish to reserve to myself any variations of modifications that may appear to those skilled in the art and fall within the scope of the following claims.

Having described my invention, I claim:

1. A fire extinguisher of the character referred to including an elongate tubular body of frangible material, a pair of longitudinally spaced oppositely disposed and outwardly opening cup-shaped partitions in the body and defining a closed central chamber and end chambers, closures releasably engaged in the ends of the body and closing the end chambers, a bomb within the central chamber, a charge of powdered fire extinguishing chemical within the chamber and packed about the bomb, a fuse extending from the bomb through one of the partitions to normally occur within the end chamber related thereto, an elongate cord fixed to and extending between the other partition and the closure related thereto and adapted to normally occur within the end chamber defined thereby, said closure related to the cord adapted to serve as a handle when the closure is removed and to facilitate slinging and casting the extinguisher into a fire, said closure related to the chamber in which the fuse is housed being removable to provide access to the fuse, the bomb being adapted, when ignited, to explode the body and distribute the chemical.

2. A fire extinguisher of the character referred to including an elongate tubular body of frangible material, a pair of longitudinally spaced oppositely disposed and outwardly opening cup-shaped partitions of frangible material engaged in the body in fixed position and defining a closed central chamber and end chambers, disc-shaped closures releasably engaged in the ends of the body and closing the end chambers, a pull tab on the closures and accessible at the exterior of the extinguisher and adapted to facilitate removal of the closures, a concussion bomb within the central chamber, a charge of powdered sodium bicarbonate within the chamber and packed about the bomb; a fuse extending from the bomb through one of the partitions to normally occur within the end chamber related thereto, an elongate cord fixed to and extending between the other partition and the closure related thereto and adapted to normally occur within the end chamber defined thereby, said closure related to the cord adapted to serve as a handle when the closure is removed and to facilitate slinging and casting the extinguisher into a fire, said closure related to the chamber in which the fuse is housed being removable to provide access to the fuse, the bomb being adapted, when ignited, to explode the body, snub the fire and distribute the sodium bicarbonate over the fire.
